CLAIM

The ornamental design for a vehicle wheel, as shown and described.

DESCRIPTION

FIG. 1 is a front perspective of a vehicle wheel showing my new design.

FIG. 2 is a rear perspective view thereof.

FIG. 3 is a front view thereof.

FIG. 4 is a rear view thereof.

FIG. 5 is a close-up front perspective view thereof; and,

FIG. 6 is another close-up front perspective view thereof.

The details shown in broken lines form no part of the claimed design.
